(57) **CLAIM**

The ornamental design for a windshield removal and replacement apparatus, as shown and described.

DESCRIPTION

FIG. 1 is a front, right perspective view of the new design for a windshield removal and replacement apparatus.

FIG. 2 is a back, left perspective view of the new design for a windshield removal and replacement apparatus.

FIG. 3 is a back view of the new design for a windshield removal and replacement apparatus.

FIG. 4 is a front view of the new design for a windshield removal and replacement apparatus.

FIG. 5 is a right side view of the new design for a windshield removal and replacement apparatus.

FIG. 6 is a left side view of the new design for a windshield removal and replacement apparatus.

FIG. 7 is a top view of the new design for a windshield removal and replacement apparatus.

FIG. 8 is a bottom view of the new design for a windshield removal and replacement apparatus.

FIG. 9 is another top view of the new design for a windshield removal and replacement apparatus.

FIG. 10 is a cross-sectional view as indicated in FIG. 9.

FIG. 11 is another cross-sectional view as indicated in FIG. 9.

FIG. 12 is a front, right perspective view of the new design for a windshield removal and replacement apparatus shown in an alternate position; and,

FIG. 13 is a right side view of FIG. 12.

The features shown in broken lines and without shading in the drawings form no part of the claimed design.

The dot-dash broken lines in FIG. 9 are for the purpose of indicating the plane upon which the sectional views are taken and form no part of the claimed design.

The oblique parallel lines in cross-sectional views FIGS. 10 and 11 are hatching lines.

1 Claim, 13 Drawing Sheets
